UNITED STATES PATENT OFFICE.

ROBERT ALEXANDER MOORE, OF NEW YORK, N. Y.

ROTARY INTERNAL-COMBUSTION ENGINE.

Application filed May 20, 1920. Serial No. 382,732.

To all whom it may concern:

Be it known that I, ROBERT ALEXANDER MOORE, a citizen of the United States, residing at New York, in the county of New York and State of New York, have invented 5 certain new and useful Improvements in Rotary Internal-Combustion Engines, of which the following is a specification.

The present invention relates to improvements in that type of rotary explosive engines in which impulses from the successive explosions are imparted to a rotary piston and more specifically to the form in which this piston is provided with peripheral cavities or piston faces so arranged as to operate with valve members to form explosive chambers whereby the impulse of the explosions take effect in the direction of the operation of the piston, while the reaction is sustained by the valve members. 20

The primary object is to provide a simple and effective construction of this character, comparatively inexpensive to manufacture, while possessing durability and efficiency in action. 25

Further objects are to provide novel means for introducing the explosive medium into the firing chambers, for ignition of the gas, for scavenging the engine of the exhaust gases, and finally for cooling the valve mechanism. 30

With these and other objects in view, the invention consists in certain novel combinations and arrangements of parts as will 35 more fully appear as the description proceeds, the novel features thereof being pointed out in the appended claims.

For a full understanding of the invention, reference is to be had to the following 40 description and accompanying drawings, in which:—

Figure 1 is a side elevation of an engine constructed in accordance with this invention, the side cover plate being removed and parts broken away and shown in section to disclose the details of construction. 45

Figure 2 is an end elevation.

Figure 3 is a detail view, partly in section, of one of the valve assemblies. 50

Figure 4 is an elevation of the device showing the fuel pumping and compressing means.

Figure 5 is a vertical sectional view, on the line 5—5 of Fig. 4.

Figure 6 is a fragmentary sectional view

of the valve ports or passages controlling the fuel supply.

Figure 7 is a perspective view of a valve member showing more clearly the configuration thereof. 60

Figure 8 is a view in elevation of the side of the engine opposite that shown in Fig. 4.

Figure 9 is a sectional view taken about on the plane indicated by the line 9—9 of Fig. 1, and 65

Figure 10 is a detail section through the air passages of the firing chamber on line 7—7 of Figure 1.

Corresponding and like parts are referred to in the following description and indicated in all the views of the drawings by the same reference numerals. 70

In general, the engine embodies a cylindrical casing 1 provided with removable covers or side plates 2 at opposite sides, 75 within which casing is journaled the rotor or rotary piston 3. The latter is of a peculiar formation in that it is formed centrally about its axis with fan blades 4 so that in the rotation of this member it functions to expel the exhaust gases and induce a circulation of air about certain parts, as will be more fully explained hereinafter. 80

At spaced intervals about the periphery of the rotor are provided a suitable number 85 of cavities or piston faces 5 somewhat elongated and relatively deep at one end from which they gradually merge to the peripheral surface. It should be noted here that the side walls of these cavities are formed with curving projections 6 constituting tracks for the valves more particularly set forth as this description proceeds. Adjacent to the shallower end and leading from each cavity is a passage 7 communicating 90 with the central fan portion of the rotor, these passages being exhaust passages. As customary the rotor is mounted upon a shaft 8 from which power is taken for the work in the usual manner. 95

In the embodiment shown, I provide a pair of rocking or oscillating valve members 9 of special construction, as will be observed from Figs. 3 and 7 of the drawings, the former figure disclosing a valve assembly and the latter a valve alone. Each of these valves comprises a hollow cylindrical body provided with a slot or opening 10, shown in Fig. 1, and with an offset or extension 11, provided with a shoulder 110

12 at each side. This extension is so constructed as to provide a series of passages 13 from the interior, opening along its curved face designated 14. The walls of 5 these passages really constitute partitions as will be apparent from Fig. 3 of the drawings.

The base of the engine is, of course, formed with suitable chambers in which 10 these valve members are disposed, that portion of each chamber in which the extension 11 of a valve is received being of sufficient size to permit the forward extension to oscillate about the axis of the valve member within limits prescribed by their end wall and the casing abutments 15 with which the shoulders 12 impinge.

Exteriorly the body of the valve member, and interiorly the chamber in which it is 20 received, are formed with corresponding grooves 16, 16' for communication with an annular groove 17, one of the latter being open to atmosphere at one side as indicated at 17'. The air under the action of the 25 rotor fan blades is drawn through the communicating passage 18 leading to the central portion of the rotor and passes to exhaust along with the exhaust gases.

The base of the engine casing constitutes a 30 storage chamber 19 in which the fuel gases are compressed by means now to be described. At one side of the casing 1 the shaft 8 is provided with a pinion 20 meshing with the crank gear 21, to the crank pin 22 35 of which are connected the piston rods 23 of the pistons of the compression pumps. The cylinders 24 of these pumps are pivotally connected to lateral projections 25, one of which is shown in Fig. 6. A passage 26 40 through each of these places the supply line 27 of the fuel in communication with the chamber 19, it being understood that suitable check valves 28, 29 are provided to permit the proper functioning of the pumping 45 mechanism to first draw in the fuel and on the in-stroke to drive it into the chamber 19 aforesaid. This need not be more specifically set forth, for it is within the purview of this invention to employ any well known 50 means for controlling the inflow of the fuel through the instrumentalities shown.

Reverting now to the valve members hereinbefore described it will be observed 55 from Fig. 3 that into the opening in one end of the valve is screwed a plug 30 carrying a spring 31 which slidably bears against a projection 32 disposed in the side of the casing, so arranged as to place the valve member under tension, that is to say, holding it firmly and yieldably against the periphery of the rotor. Into the opposite end 60 of the valve member is screwed a spark plug 33 which carries a wiper finger 34 adapted to yieldably contact with the electric contact 35 mounted in the terminal

block 36 secured to the side of the casing intermediate the two valve members. The motion of the valves is such that the respective fingers 34 will alternately impinge this contact to which an electric current from a 70 suitable source is supplied through the conductors 37. This provides a very simple ignition system, though I do not wish to be confined to the particular embodiment herein illustrated for this purpose. 75

In the operation of the engine the fuel under the compression in the chamber 19 passes through suitable passages 38 and into the respective valves as their inlets 10 register with the said passages. At the proper 80 moment the charge is ignited and the force of the explosion is imparted to the rotor through the passages 13 and against the wall of the piston pocket in which the valve extension has moved. It will, of course, be 85

understood that the valve members in the rotation of the rotor contact with the periphery of said rotor and immediately one of the cavities 5 reaches a valve member the extension thereof moves into said cavity under the action of the spring tension or other means until it occupies the position shown at the right of Fig. 1. In this position the explosion takes place and it will be observed 90 that the force of the impulse takes effect against the end wall or piston face of the cavity so to speak, while the reaction of the impulse is against the end of the valve member substantially in a direction radially of the axis of said valve member. As the 95 rotor moves under the impulse the valve member extension is shifted outwardly by the formation of the cavity, and as the end of said extension passes the passage 7 of the rotor the exhaust gases are drawn from 100 the cavity by the action of the fan and discharged through the openings 39 in the sides of the rotor casing. Any exhaust gases from a previous explosion which may back up into the cavity in the rear of the valve 105 extension are obviously permitted to escape or are forced out of the passage 7 in this movement of the valve member. The valve members are so arranged, that it will be apparent that they will ride into these cavities 110 5 successively so that the impulse will take place rapidly one after another to impart continuous and steady impulse to the rotor. 115

As this action above described takes place the motion of the rotor draws the air through the exterior valve passages in the manner hereinbefore described so that these valves are always maintained suitably cooled to permit of the proper operation of the device. The rotation of the piston in the manner described places the pumping mechanism in operation so that the fuel supply in the chamber 19 is maintained sufficient for the purposes of continuing the 120 operation of the engine. It need be added 125 130

only that the rocking movement of the valves as they pass into and out of the cavities in the manner above described shifts the spark plug fingers 34 into alternate engagement with the contact post 35 to fire the fuel charge at the proper moment.

It will be obvious from the foregoing description that an engine constructed in accordance with this invention possesses material advantage over the ordinary reciprocating piston type of engine, in that it is composed of a relatively few parts and these are subject to a minimum amount of wear and produce a minimum amount of friction.

Slight changes may obviously be made in the details of construction without departing from the spirit of the invention, and within the scope of the claims hereto appended.

Having thus described my invention, what I claim as new and desire to secure by Letters Patent, is:—

1. In a rotary internal combustion engine, the combination with a casing, of a rotor mounted therein and formed with piston faces, a valve movable into and out of cooperative relation with the faces, the movement of the valve automatically controlling the admission of the charge, and ignition means including a fixed contact element and a movable contact element, the latter being mounted upon and carried by the valve so as to be movable therewith and arranged to be brought into engagement with the fixed contact at the proper time.

2. In a rotary internal combustion engine, the combination with a casing, of a rotor mounted therein and formed with piston faces, a pivotally mounted valve member adapted to swing into and out of cooperative relation with the faces, the movements of the valve automatically controlling the admission of the explosive charge, and ignition means including a fixed contact element and a movable contact element, the latter being rigidly connected to the valves so as to be swung into engagement with the fixed contact at the proper time to explode the charge.

3. In a rotary internal combustion engine, the combination with a casing, of a rotor mounted therein and formed with piston faces, a hollow valve pivotally mounted upon the casing and adapted to swing into and out of cooperative relation with the faces, the swinging movements of the hollow valve serving to automatically control the admission of the charge thereto, a spark plug projecting axially into the hollow valve at one end thereof, and ignition means including a fixed contact element and a swinging contact element, the latter being carried by the spark plug and adapted to be

swung into and out of engagement with the fixed contact element by the movements of the valve.

4. In a rotary internal combustion engine, the combination with a casing, of a rotor mounted within the casing and provided with a series of piston faces, a hollow valve member pivotally mounted within the casing and adapted to swing in and out in cooperative relation to the faces, a plug axially applied to one end of the hollow valve, spring means cooperating with the plug to swing the valve into operative position, a spark plug axially applied to the opposite end of the hollow valve so as to rotate therewith, and contact means associated with the spark plug and adapted to be controlled automatically by the swinging movements of the valves.

5. In a rotary internal combustion engine, the combination with a casing, of a rotor mounted within the casing and provided with a peripheral series of piston faces, valve means cooperating successively with the faces to provide firing chambers and controlling the admission of an explosive charge to the firing chambers, fan members mounted upon the rotor and providing a means for positively scavenging the engine, and means associated with the fan members for circulating air around the valves to cool the same.

6. In a rotary internal combustion engine, the combination with a casing, of a rotor mounted within the casing, said rotor being formed with a peripheral series of piston faces and a centrally disposed fan chamber, a hollow valve mounted for successive engagement with the faces to provide firing chambers, means for exploding the charge in the hollow valve, air passages being provided around the valve and in communication with the fan chamber of the rotor, and fan blades mounted upon the rotor and arranged within the fan chamber to cause a circulation of air through the before mentioned passages to cool the hollow valve.

7. In a rotary internal combustion engine, the combination with a casing, of a rotor mounted within the casing and provided with a peripheral series of piston faces and a central fan chamber, a hollow valve arranged for successive engagement with the faces of the rotor for cooperation therewith to provide firing chambers, means for igniting the charges in the hollow valve, air passages being provided around the hollow valve and exhaust passages being provided in the rotor between the periphery thereof and the fan chamber, and fan blades rigid with the rotor and arranged within the fan chamber thereof, said fan blades operating to produce a circulation of air whereby the engine is positively scavenged and the hollow valve member cooled.

8. In a rotary internal combustion engine, the combination with a casing, of a rotor mounted within the casing and provided with piston faces, a hollow valve member 5 pivotally mounted within the casing and adapted to be swung into cooperative relation with the faces, removable plugs axially applied to the hollow valve member at opposite ends thereof so as to rotate therewith, 10 a spring associated with one of the plugs for swinging the valve member into operative position, and ignition means associated with the opposite plug for exploding the charge within the hollow valve member.
- 15 9. In a rotary internal combustion engine, the combination with a casing, of a rotor mounted within the casing, a hollow member movably mounted within the casing and operatively associated with the rotor to provide a combustion chamber within which the explosive charges are fired, fan members 20 driven by the rotor, and means associated with the fan members for positively circulating air between the casing and hollow member to cool the same.
- 25 10. In a rotary internal combustion engine, the combination with a casing, of a rotor mounted within the casing and cooperating with the rotor to provide a firing chamber, the casing having a fan chamber and being also provided with an air passage leading from the fan chamber around the firing chamber, and a fan actuated by the rotor and operating to positively circulate air from the fan chamber through the 30 before mentioned air passage and around the firing chamber to cool the walls of the latter.
11. In a rotary internal combustion engine, the combination with a casing, of a 35 rotor mounted therein, a member pivotally mounted within the casing and cooperating with the rotor to provide a combustion chamber, the casing being provided with an air passage leading to the bearings of the pivotally mounted member, and a fan actuated by the rotor for forcing air through the said passage and around the bearings of the pivotally mounted member.

In testimony whereof I affix my signature.

ROBERT ALEXANDER MOORE.
